The ornamental design for an apparatus for repairing punctured tires, as shown and described.

(51) **LOC (9) Cl.** **15-99**

DESCRIPTION

(52) **U.S. Cl.** **D15/199**

FIG. 1 is a front perspective view of an apparatus for repairing punctured tires.

(58) **Field of Classification Search** D8/105,

FIG. 2 is a rear perspective view thereof.

D8/499; D15/199; 141/38, 67, 100; 152/415

FIG. 3 is a front elevation view thereof.

See application file for complete search history.

FIG. 4 is a rear elevation view thereof.

(56) **References Cited**

FIG. 5 is a top plan view thereof.

U.S. PATENT DOCUMENTS

FIG. 6 is a bottom plan view thereof.

4,284,451 A * 8/1981 Conley 156/97

FIG. 7 is a left side elevation view thereof; and,

6,283,172 B1 * 9/2001 Thurner 141/38

FIG. 8 is a right side elevation view thereof.
